COMPARTMENTED FIBEROBOARD EGG CASE

Reynolds Guyer, St. Paul, Minn., assignor to
 Waldorf Paper Products Company, St. Paul,
 Minn., a corporation of Minnesota

Application April 29, 1943, Serial No. 484,963

15 Claims. (Cl. 229—15)

1

My invention relates to an improvement in egg case and method of forming the same, wherein it is desired to produce a case capable of holding a considerable quantity of eggs or other goods, which case is formed entirely of cellulosic sheet material.

For many years, attempts have been made to produce egg cases of fibrous sheet material such as of fiber board or of corrugated paper board. While some of these cases thus formed have worked out satisfactorily, difficulty has been experienced in forming a case which is simple to assemble and which may be made at a sufficiently low cost to compete with inexpensive wooden cases for the same purpose.

An object of the present invention lies in the provision of an egg case which may be manufactured at a low cost and with a relatively small amount of material and yet it may be assembled in a simple manner. Accordingly the cases thus formed may be shipped in flat formation and may be assembled by the producer in an extremely short time.

A feature of the present invention lies in the provision of an egg case having reinforced end walls so as to withstand compression. A further feature of the invention lies in the provision of a case which is simple to open and close and which when closed has little tendency to open.

A further feature of the present invention lies in the provision of a case which includes a rectangular shell which may be folded flat when not in assembled form and in the provision of a pair of additional elongated strips which form a central separating partition, a case bottom, reinforcing end wall portions, and foldably attached cover elements. When these two elements are added to the rectangular shell construction a complete egg case is formed.

An additional feature of the present invention lies in the provision of a form by means of which the parts of the case may be easily assembled. Such a form may be provided for the use of the producer so that the cases may be shipped in flat condition and assembled in a small period of time.

An additional feature of the present invention lies in the provision of a locking means which prevents outward bowing of the case walls when the cover members are in closed position.

These and other objects and novel features of my invention will be more clearly and fully set forth in the following specification and claims.

In the drawings forming a part of my specification:

2

Figure 1 is a perspective view of my egg case in readiness for filling.

Figure 2 is a longitudinal section through the case showing the construction thereof.

Figure 3 is a top perspective view of the shell, the bottom of the case being broken away.

Figure 4 is a bottom perspective view of the case shell, the top thereof being broken away.

Figure 5 is a perspective view of the case completing strip elements in folded relation much as they would appear when in position within the shell shown in Figures 3 and 4.

Figure 6 is a diagrammatic view showing the died-out form of the case completing strip.

15 Figure 7 is a diagrammatic view showing the died-out formation of the blank forming the case shell.

Figure 8 is an enlarged sectional view through the central partition member when the cover of 20 the case is closed.

Figure 9 is a perspective view of the form used in assembling the cases.

Figure 10 is a view of the form shown in Figure 9 with the case shell mounted thereon.

25 Figure 11 is a perspective view of the case shell with the case completing strips partially installed thereto.

Figure 12 is a perspective view similar to Figure 11 showing the next step in assembling the case completing strip within the shell.

30 The egg case A includes an outer rectangular shell 10 and a pair of case forming elements 11 and 12. The case forming elements 11 and 12 are identical in formation but have been given different identification numerals in view of the fact that they may be individually operated.

The enclosing shell 10 may be formed of a single length of fiber board or the like, but for the sake of economy and simplicity of handling, the shell 35 40 10 is formed of two separate elements 13 and 14 connected together. Both the elements 13 and 14 are identical in form, but have been given separate identification numerals for simplicity of explanation.

45 Each of the shell sections 13 and 14 include a wall panel 15 connected along a fold line 16 to an end panel 17. The end panel 17 is connected along the fold line 19 parallel to the fold line 16 to an attachment flap 20. The attachment flap 50 55 20 of the section 13 overlap the free edge 21 of the side panel 15 of the shell section 14. Similarly the attachment flap 20 of the shell section 14 overlaps the edge 21 of the end panel 17 of the section 13. Obviously the sections 13 and 14 could be connected along a fold line rather than

having these sections connected by staples such as 22.

Along the upper edge of the side panel 15 are connected a pair of flaps 23 and 24 which are connected to the side wall panel 15 along the common fold line 25. These flaps 23 and 24 are separated by a slot 26 which extends from the free edge of the flaps to the fold line 25. Opposed projecting ears 27 are provided on the adjacent ends of the flaps 23 and 24 for a purpose which will be later described in detail.

As elongated flap 29 is connected along a fold line 30 to the lower edge of the panel 15 of each section 13 and 14. This flap 29 is provided with a central notch 31 for a purpose which will be later more clearly described. A flap 32 is connected along a fold line 33 to each end panel 17. The panel 17 is also preferably die cut in channel-shaped formation along the line 34 to form a flap 35 foldably connected to the panel 17 along the fold line 36. The fold line 36 is spaced from the top of the panel 17 a distance substantially equal to the width of the flap 32.

As best illustrated in Figure 6 of the drawings, the case forming strips 11 and 12 are both formed as illustrated in Figure 6 of the drawings. These strips 11 and 12 comprise an end flap 37 connected along a fold line 39 to a partition panel 40. The partition panel 40 is connected along a fold line 41 to a bottom panel 42. This bottom panel is connected along a fold line 43 to the end wall reinforcing panel 44. The reinforcing panel 44 is connected along the fold line 45 to a top cover panel 46. This cover panel 46 is foldably connected along the line 47 to an end flap 48 having beveled corners 50.

The fold line 39 includes a pair of channel-shaped die cuts 51 which form short projecting ears 52 which will be more fully described. The fold line 41 is provided with a pair of opposed edge notches 53 which extend along the fold line 41 from opposed edges of the strip.

In the formation of the crate A the rectangular shell 10 is preferably inverted and the case forming strip elements 11 and 12 held in contiguous relation are inserted into the shell centrally so as to be midway between the end panels 14 of the shell and parallel thereto. When the fold line 41 is moved to a position adjacent the upper edges of the flaps 29, these flaps are folded inwardly to extend at right angles to the side walls 13 of the sleeve with the portion of the flaps 29 between the base of the slots 31 and the fold line 30 embraced in the slots 53 of the strips 11 and 12. It will also be noted that the slots 31 then embrace a portion of the strips 12 and 13, thus interlocking the flaps 29 with the strips 12 and 13.

The end flaps 48 of the strips 12 and 13 are then inserted within the end walls 14 of the shell, one strip 11 being inserted within one end wall 14, while the other strip 12 extends within the opposite wall 14. These strips 11 and 12 are inserted until the panels 44 thereof lie interiorly of the walls 14, whereupon the panels 42 form the bottom of the case at the same time the panel 46 and the end flaps 48 project beyond the top of the shell to provide an open top case which may be closed by the two panels 46 of the strips 11 and 12.

To accomplish this assembly in a simple manner the form best illustrated in Figure 12 of the drawings may be used. This form includes a pair of spaced end supports 54 and 55 in parallel relation connected by laterally extending connect-

ing bars 56. The end supports 54 and 55 are so spaced as to permit the shell 10 to encircle the same and so that when the shell is in the unfolded position illustrated in Figure 10 of the drawings, the free edges of the flaps 23 and 24 rest upon the connecting bars 56 so as to limit downward movement of the shell 10.

A pair of spaced table elements 57 and 59 are arranged in coplanar relationship at the upper extremity of the supports 54 and the adjacent edges of these table portions 57 and 59 are supported by spaced vertical supports 60 and 61. Thus a slotted table is formed for supporting the shell 10 so that the top of the table is substantially even with the fold lines 30 of the shell 10 when the shell is supported in inverted position thereupon.

In assembling the case A, the shell forming elements 13 and 14 are first connected together in any suitable means such as by the staples 22 to form a rectangular wall portion. The case forming strips 11 and 12 are placed in contiguous relation and the end flaps 37 and partition forming flaps 40 are inserted in the slot formed between the spaced vertical supports 60 and 61, as illustrated in Figure 11 until the slots 53 are adjacent the slots 31 in the flaps 29. Thereafter as the strips 11 and 12 are forced downwardly the flaps 29 are bent inwardly so that the slots 31 and 53 inter-engage and so that the slots 31 embrace a portion of the strips 11 and 12 and so that the slots 53 embrace a portion of the flaps 29. The flaps 29 are thus folded flat upon the table tops 57 and 59 at right angles to the side panels 15, as best illustrated in Figure 12 of the drawings.

The vertical supports 54 and 55 are so spaced as to provide a slot between each vertical support and the adjacent end wall 17 of the shell 10. Into each vertical slot is inserted an end flap 48 of one of the strips 11 or 12. The strips are then forced downwardly through the slots within the side walls 17 in the manner illustrated in Figure 12 of the drawings until the panels 44 lie interiorly of the end panels 17 and until the bottom panels 42 of the strips lie in contacting relation with the folded flaps 29.

When in this position the crate A is assembled and is in readiness for filling. The crate is usually filled by placing the eggs on suitable egg flats made particularly for the purpose and the eggs are arranged in superimposed layers to a point adjacent the top of the case. The egg flats are ordinarily substantially rectangular in shape and both sides of the crate on opposite sides of the partition walls 46 are filled with eggs. When the crate has been completely filled the flaps 23 and 24 are folded down into right angular relationship with the side panels 15, and the end flaps 37 are folded down to overlie the adjacent ends of these flaps 23 and 24. The cover panels 46 are then folded down from the outer side walls and the end flaps 48 are inserted between the partition walls 40 as best illustrated in Figure 2 of the drawings. This action separates the partition walls 40. This separation of the partition walls 40 acts to lock the flaps 23 and 24 from lateral movement in a manner which will be hereinafter set forth. When thus closed a strip of paper adhesive tape or the like, indicated in Figure 2 of the drawings by the numeral 62 is placed over the seam between the cover flaps 46 and to extend partially over the opposed side wall panels 15.

I prefer to fold the flaps 35, formed by the die cut line 34, upwardly to overlie a portion of the end walls 17, as best illustrated in Figure 2. The

flaps 32 may then be folded along the fold line 33 to overlie the flaps 35. The flaps 32 may be held in folded position by staples 64 or other suitable means. A hand hold having a rounded lower edge is thus provided.

I have described the fact that ears 52 are formed between the end flaps 37 and the partition panels 40 by die-cut lines 51. These ears 52 form apertures in the partition panels 40 below the fold lines 39 at the upper extremity of the panels 40, which may be engaged by the ears 27 on the flaps 23 and 24. When the flaps 23 and 24 are folded down into the position shown in Figures 1, 2, and 8 of the drawings, the openings formed by cutting out the ears 52 are in alignment with the ears 27. Therefore when the end flaps 49 are inserted between the partition walls 40, these partition walls 40 are forced apart, urging the ears 27 through the apertures 65 formed adjacent the top of the partition walls 40. When thus locked as best illustrated in Figure 8 of the drawings, the flaps 23 and 24 are held from lateral movement, thus preventing outward bowing of the side wall panels 25 away from the vertical edges of the partition walls 40.

Ventilating openings 66 of any desired shape are provided in the side walls 15 to permit a circulation of air through the case. These openings may be placed in any strategic position, but are preferably formed through the side wall panels 15 in view of the fact that these panels are of single thickness.

In accordance with the patent statutes, I have described the principles of construction and operation of my egg case and of the method of forming the same, and while I have endeavored to set forth the best embodiment thereof, I desire to have it understood that obvious changes may be made within the scope of the following claims without departing from the spirit of my invention.

I claim:

1. An egg case comprising a substantially rectangular shell having side and end walls, foldably connected flaps on the lower edge of said side walls, a pair of compartment forming members within said shell each comprising a partition wall in interlocking relation with said flaps, a bottom wall designed to underlie said flaps, and an end reinforcing wall arranged in parallel contacting relation with an end wall of said shell.

2. An egg case comprising a rectangular shell having connected side and end walls, and a pair of egg compartments within said shell each comprising parallel walls enclosed between the end walls of said shell and extending substantially parallel thereto, a bottom wall connecting said parallel walls, and a top wall foldably connected to one of said parallel walls, said shell having flaps issuing from the upper and lower edges of said side walls, the flaps on the lower edges of said side walls overlying said bottom wall and the flaps issuing from the upper edge of said side walls underlying said top wall.

3. An egg case comprising a substantially rectangular shell having side and end walls and foldably connected flaps issuing from the upper and lower edges of said side walls, a pair of compartments within said shell, each comprising a partition wall substantially parallel to said end walls, a bottom wall underlying said flaps on the lower edge of said side walls, and an end wall reinforcing panel extending parallel to and adjacent the end walls of said shell, and a top panel foldably connected to said end wall reinforcing

panel, said top panel arranged to overlie said flaps issuing from the upper edges of said side walls.

4. An egg case comprising a substantially rectangular shell having side and end walls, flaps issuing from the upper and lower edges of said side walls, a pair of compartments within said shell, each of said compartments being formed by a compartment forming strip, said compartment forming strip comprising an end flap designed to overlie said end flaps on the upper edges of said side walls, a partition wall arranged to extend substantially parallel to the end wall of said shell, a bottom wall designed to extend beneath the flaps issuing from the lower edges of the side walls of said shell and an end wall reinforcing panel designed to extend parallel to and adjacent an end wall of said shell.

5. A shipping case comprising a rectangular body shell having side and end walls, flaps issuing from the upper and lower edges of said side walls, and a pair of compartments within said shell, each said compartment being formed by an end flap adapted to overlie the flaps issuing from the upper edges of said side walls, a partition panel extending substantially parallel to said end walls of said shell, a bottom panel arranged to underlie said flaps issuing from the lower edges of said side walls, an end wall reinforcing panel designed to extend parallel to and adjacent an end wall of said shell, a top panel foldably connected to said end wall reinforcing panel, and a cover tongue foldably connected to said cover panel, the tongues of said two cover forming strips designed to extend between said partition forming panels.

6. An egg case comprising a rectangular body shell having a substantially open bottom, and a pair of strip elements of a width substantially that of the inner width of the shell positioned in the shell, flaps on the bottom edge of the shell in interlocking relation with said strip elements holding said strip elements from vertical movement, each said strip element including a partition wall panel, a bottom panel foldably connected thereto, and an end reinforcing wall panel foldably connected to said bottom panel, said partition wall panels being in opposed parallel relation, and said bottom panels forming the case bottom.

7. An egg case comprising a rectangular body shell having a substantially open bottom, and a pair of strip elements of a width substantially that of the inner width of the shell positioned in the shell, flaps on the bottom edge of the shell in interlocking relation with said strip elements holding said strip elements from vertical movement, each said strip element including a partition wall panel, a bottom panel foldably connected thereto, an end reinforcing wall panel foldably connected to said bottom panel, and a top panel foldably connected to said reinforcing wall panel, said partition wall panels being in opposed parallel relation, and said bottom panels forming the case bottom.

8. An egg case comprising a rectangular body shell having a substantially open bottom, and a pair of strip elements of a width substantially that of the inner width of the shell positioned in the shell, flaps on the bottom edge of the shell in interlocking relation with said strip elements holding said strip elements from vertical movement, each said strip element including a partition wall panel, a bottom panel foldably connected thereto, an end reinforcing wall panel

foldably connected to said bottom panel, a top panel foldably connected to said reinforcing wall panel, and an end flap foldably secured to said top panel, said partition wall panels being in opposed parallel relation, and said bottom panels forming the case bottom.

9. An egg case comprising a rectangular body shell having a substantially open bottom, and a pair of strip elements of a width substantially that of the inner width of the shell positioned in the shell, flaps on the bottom edge of the shell in interlocking relation with said strip elements holding said strip elements from vertical movement, each said strip element including a partition wall panel, a bottom panel foldably connected thereto, an end reinforcing wall panel foldably connected to said bottom panel, and an end flap foldably connected to said partition wall panel, said partition wall panels being in opposed parallel relation, and said bottom panels forming the case bottom.

10. An egg case comprising a rectangular body shell having a substantially open bottom, and a pair of strip elements of a width substantially that of the inner width of the shell positioned in the shell, flaps on the bottom edge of the shell in interlocking relation with said strip elements holding said strip elements from vertical movement, each said strip element including a partition wall panel, a bottom panel foldably connected thereto, an end reinforcing wall panel foldably connected to said bottom panel, a top panel foldably connected to said reinforcing wall panel, an end flap foldably secured to said top panel, and an end flap foldably connected to said reinforcing wall panel, said partition wall panels being in opposed parallel relation, and said bottom panels forming the case bottom.

11. An egg case comprising a rectangular body shell having a substantially open bottom and top, and a pair of strip elements of a width substantially that of the inner width of the shell positioned in the shell, top flaps on the upper edge of the shell, bottom flaps on the bottom edge of the shell in interlocking relation with said strip elements holding said strip elements from vertical movement, each said strip element including a partition wall panel, a bottom panel foldably connected thereto, an end reinforcing wall panel foldably connected to said bottom panel, and a top panel connected to said reinforcing wall panel, said top panels overlying said top flaps of said shell, said partition wall panels being in opposed parallel relation, and said bottom panels forming the case bottom.

12. An egg case comprising a rectangular body shell having a substantially open bottom and top, and a pair of strip elements of a width substantially that of the inner width of the shell positioned in the shell, top flaps on the upper edge of the shell, bottom flaps on the bottom edge of the shell in interlocking relation with said strip elements holding said strip elements from vertical movement, each said strip element

including a partition wall panel, a bottom panel foldably connected thereto, an end reinforcing wall panel foldably connected to said bottom panel, and an end flap on said partition wall panel, said end flap overlying said top flaps of said shell, said partition wall panels being in opposed parallel relation, and said bottom panels forming the case bottom.

13. An egg case comprising a rectangular body shell having a substantially open bottom and top, and a pair of strip elements of a width substantially that of the inner width of the shell positioned in the shell, top flaps on the upper edge of the shell, bottom flaps on the bottom edge of the shell in interlocking relation with said strip elements holding said strip elements from vertical movement, each said strip element including a partition wall panel, a bottom panel foldably connected thereto, an end reinforcing wall panel foldably connected to said bottom panel, an end flap on said partition wall panel, and a top panel connected to said reinforcing wall panel, said top panel and said end flaps overlying said top flaps of said shell, said partition wall panels being in opposed parallel relation, and said bottom panels forming the case bottom.

14. An egg case comprising a rectangular body shell having a substantially open bottom and top, and a pair of strip elements of a width substantially that of the inner width of the shell positioned in the shell, top flaps on the upper edge of the shell, bottom flaps on the bottom edge of the shell in interlocking relation with said strip elements holding said strip elements from vertical movement, each said strip element including a partition wall panel, a bottom panel foldably connected thereto, an end reinforcing wall panel foldably connected to said bottom panel, a top panel connected to said reinforcing wall panel, a cover tongue connected to said top panel, and an end flap foldably connected to said partition wall panel, said cover tongues of said two top panels extending between said partition forming panels, said top panels and said end flaps overlying said top flaps on said shell, said partition wall panels being in opposed substantially parallel relation, and said bottom panels forming the case bottom.

15. A shipping case comprising a substantially rectangular shell including side and end walls, a pair of flaps issuing from the upper edges of each of said side walls, a partition wall within said shell extending substantially parallel to said end walls and connecting said side walls, said connection comprising an opening in said partition spaced from the side edges thereof and at least one flap on each side of the shell having a projection at one end thereof spaced from the hinge line of the flap and extending into the opening to lock said side walls from separation or bowing outwardly adjacent the ends of said partition wall.

REYNOLDS GUYER.
